W. J. RILEY

SHINGLE FASTENER

Filed Sept. 10, 1923

Inventor.
William J. Riley
By James R. Hodder
Atty.

UNITED STATES PATENT OFFICE.

WILLIAM J. RILEY, OF BOSTON, MASSACHUSETTS.

SHINGLE FASTENER.

Application filed September 10, 1923. Serial No. 661,792.

To all whom it may concern:

Be it known that I, WILLIAM J. RILEY, a citizen of the United States, and resident of Boston, in the county of Suffolk and State 5 of Massachusetts, have invented an Improvement in Shingle Fasteners, of which the following description, in connection with the accompanying drawings, is a specification, like letters on the drawings representing like 10 parts.

My present invention is a novel and improved shingle fastener, adapted for use in connection with roofing shingles, and is adapted to improve and perfect the combination 15 of a metallic shingle fastener and shingles, such as is illustrated in the prior application of William J. Riley and Hugh MacInnes, Ser. No. 621,718, filed February 28, 1923.

20 In the development of the art of roofing, particularly by means of flexible composition shingles, it is important to provide means for fastening, alining, holding and interlocking the shingles, either with or

25 without specially formed, cut or prepared shingles. My present invention is adapted particularly to provide a fastening member, preferably metallic, which can be utilized to hold, aline, maintain and interlock shingles, whether composition or of other material, in a firm, rigid and permanent manner, either with or without special notching, slotting, cutting or forming the shingles themselves, and in a manner to permit great 30

35 speed in laying a roof utilizing my improved fastener. In the said prior application, wherein is illustrated one type of shingle fastener and interlocking shingle, it was necessary to specially prepare or form the shingle itself, and also the fastener therein illustrated preferably employed projecting or interlocking flanges extending from opposite sides of the body of the fastener itself.

40 In my present invention I have devised an improved form of fastener adapted for interlocking use with a shingle, either specially prepared, notched or cut, or of plain, square angles, and also with the interlocking flanges of the metallic fastener all projecting from 45 one side. This permits closer and tighter laying of the shingles, giving a smoother and better wear-resisting, as well as waterproof construction, while at the same time greatly expediting and simplifying the laying 50 operation. In the said prior application is claimed broadly the combination of

a metallic fastener and shingle, particularly the composition type, and in the present application I have claimed my improved form of fastener. 60

Referring to the drawings illustrating preferred embodiments of the invention,

Fig. 1 is a fragmentary partial view of a shingled roof employing my fastener, and utilizing shingles of substantially octagon 65 shape;

Fig. 2 is a view illustrating my fastener applied to shingles without the octagon form;

Fig. 3 is a plan view of the notched and 70 octagon form of shingles employed in Fig. 1;

Fig. 4 is a diagrammatic side view of my fastener on the line 4—4 of Fig. 1;

Figs. 5 and 6 are plan and side views respectively of the fastener illustrated in Fig. 1; and

Figs. 7 and 8 are plan and side views respectively of the fastener illustrated in Fig. 2. 80

As shown in the drawings, the form of metallic fastener and interlocking shingle illustrated in Figs. 1, 3 and 4, comprise a shingle 1 which may be and preferably is of composition, such as fire resisting asphaltum 85 or the like, being of substantially rectangular form but with three of the corners as designated at 2, 3 and 4, slightly cut off or of octagon form. The topmost corner 5 need not be so cut or prepared. Preferably 90 also a pair of notches 7 and 8 are formed in this type of shingle, which is adapted to be utilized with my metallic fastener 10. This fastener includes a plate or body portion having one or more recesses 11 and 12 95 through which the retaining nails may be driven, and a set of upturned flanges, all being on one side of the plate 10. These flanges consist in a bottom flange 15 and a pair of side flanges 16, 16, the latter being 100 in position to engage the notches 7 and 8 respectively of the shingle shown in Figs. 1 and 3. The lower flange 15 engages the truncated portion 3, the remaining cut portions 2 and 4 being adapted to abut against 105 the adjoining shingles. This construction provides a firm, rigid, holding, aligning and interlocking roof construction, with the overlapping and abutting ends of adjacent shingles firmly united. 110

In the modified form of my fastener illustrated in Figs. 2, 7 and 8, I utilize shingles

20 of rectangular form, either with or without the cut portions 2, 3 and 4, this being entirely optional in connection with the metallic fastener 21 illustrated in this form. The 5 notches 7 and 8 are entirely omitted, as I so form the side flanges 23 and 24 in this type of fastener 21 as to engage the straight adjacent edge portion of the shingles 20 independently of notches or special formation, 10 these flanges 23 and 24 being positioned at an angle and preferably at right angles to each other and cooperating with the bottom flange 25 to interlock with the end, point or truncated section 3 of the shingle. The recesses 26 and 27 receive the fastening nails 15 and hold the fastener, together with the adjacent underneath shingle in firm position.

In both forms of my present fastener the same can be made of thin metal, stamped 20 out with the flanges 15 and 16 in one form, or 23, 24 and 25 in the other form on the same side, and at a single stamping operation, and all flanges are positioned at one side of the body portion, thus facilitating 25 the holding and interlocking action of fastener and shingles in a substantially flat position. In both forms of the invention also, the shingles are made without bends, and in one form substantially without cutting, 30 notching or other treatment, while the laying of a roof with my improved form of fastener is capable of great speed, by unskilled labor, and results in an extremely attrac-

tive waterproof and permanent construction. The fasteners act substantially as 35 automatic alining devices, as well as interlocking retaining means for the adjacent abutting shingles. I believe that the invention of a fastener, having interlocking engagement with a plurality of shingles on 40 the same side of the body portion, viz., three shingles as herein shown, is a distinct novelty, and the advantage of this construction in speed, simplicity and the facility for having all shingles and fastener lying substantially flat, is of great importance, and I wish 45 to claim the same herein broadly.

My invention is further described and defined in the form of a claim as follows:

A shingle fastener of the kind described, 50 comprising a body portion, adapted to underlie a plurality of shingles, flanges formed integral therewith and at each side thereof, adapted to interlock with shingles arranged side by side and overlying the body portion, 55 a flange formed integral with said body portion at the lower end thereof and between the first said flanges and adapted to interlock with a shingle overlying the shingles arranged side by side, and means for permitting fastening of the fastener in position.

In testimony whereof, I have signed my name to this specification.

WILLIAM J. RILEY.
